(57) **CLAIM**

The ornamental design for a protective face mask with ear coverings, as shown and described.

DESCRIPTION

FIG. 1 is a perspective view of a protective face mask with ear coverings showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof, shown in a used condition with a human figure in broken lines.

The broken lines shown in the drawings represent portions of a protective face mask with ear coverings that form no part of the claimed design. The human figure shown in broken lines in FIG. 8 forms no part of the claimed design.
